UNITED STATES PATENT OFFICE.

WARREN R. WALKER, OF GREAT KILLS, NEW YORK, ASSIGNOR TO COOPER HEWITT ELECTRIC COMPANY, OF HOBOKEN, NEW JERSEY, A CORPORATION OF NEW JERSEY.

LIQUID-FLOW SWITCH.

Application filed April 21, 1925. Serial No. 24,753.

My present invention relates to electric switches of the liquid flow type and particularly to such a switch wherein is provided means for protecting the wall of the switch envelope proper from the effects of any arcing produced during the operation of the switch.

In the switch described and claimed below are combined features which permit the making of a compact and durable switch capable of making and breaking current paths carrying high amperages and inductive loads.

In the drawing forming part of this application:

Fig. 1 is a vertical elevation view in section taken longitudinally through the center of a mercury switch embodying my invention having an outer envelope of vitreous material such as glass and electrodes sealed thereto at each end, one of which terminates within a cup of vitreous material formed integral with the wall of said envelope with vitreous insulating material extending over and actually covering the electrode between said cup and the envelope wall, and a sleeve of highly refractory vitreous material such as fused silica and adapted to shield the envelope wall from any arcing which occurs during the operation of the switch.

Fig. 2 is a sectional view taken along the line 2—2 of Fig. 1,

Fig. 3 is a sectional view showing an electrode cup for the switch and the electrode and cup stem therefor and showing the cup stem proper as being made of a material suitable for the sealing therethrough of the electrode and a cup of more highly refractory material to withstand the arcing occurring during the operation of the switch and a graded seal between the stem proper and the electrode cup, and,

Fig. 4 is a sectional view showing an electrode cup preferably of the same material as that of the switch envelope but having formed along the edge of the opening thereof a rim having an outward drag and a ferrule of highly refractory material such for example as fused quartz formed as an annular channel with an inward drag or curve on the outer member thereof, the ferrule being held on the rim of the cup by means of a suitable cement between the outwardly drag

member of the cup and the inwardly drag member of the ferrule.

In Figs. 1 and 2 of the drawing the sealed envelope 1 as of a boro-silicate glass, has sealed therethrough at one end the electrode 2 as of tungsten which is covered on that portion thereof which extends into the switch and to within a short distance of the inner end by a coating 3 as of a boro-silicate glass which coating is made integral with the wall of the envelope. As shown in the drawing this electrode preferably extends downwardly toward the interior of the switch. The similarly mounted and inclined electrode 4 is sealed in through the opposite end of the switch and has over the surface of its inner portion a coating 5 of the material of the envelope formed integral with the envelope 1 which coating terminates in a cup 6 formed about the inner end of the electrode 4 and opening upwardly into the interior of the envelope 1. Within the envelope 1 and extending substantially the length thereof about said electrodes is mounted the sleeve 7 of highly refractory vitreous material such for example as fused silica. This sleeve 7 fits fairly closely in the envelope 1 and is slipped thereto before the drawing down and closing of one end of the envelope. The body of mercury 8 serves for connecting electrodes 2 and 4 and for breaking the path therebetween by flow thereof during the operating of the switch in a manner well known in the operation of this type of switches.

In Fig. 3 is shown a cup 6' sealed to the electrode coating 5 and a graded seal 10. Said cup 6' is of a very highly refractory material such as fused silica and the coating 5 is for example of a glass such as boro-silicate glass suitable for the sealing-in of a metal such as tungsten of which electrode 4 is made and the graded seal 10 such for example as graded mixtures of fused borates and silicates is provided between the sleeve 5 and the cup 6' in a manner well known in the glass working art.

In Fig. 4 is shown a cup 6 as in the switch of Fig. 2, but having formed along the edge of the opening thereof a rim 11 which has an outward drag. The cup 6 like rim 11 is preferably made of the same material as the switch envelope 1 shown in Fig. 1 which is in a preferred form of boro-silicate glass,

On the rim 10 is seated a ferrule 12 which has the shape of an annulus with an inverted U shaped cross section, the outer member 13 of which is given an inward drag which 5 serves together with the outwardly drag rim 11 to lock said ferrule and the cup through the medium of a filling 14 of a suitable cement interposed therebetween, such cement being for example of fused 10 silver chloride. The ferrule 12 in the use of the switch serves to protect the material of the cup 6 from any arc produced during the opening or closing of electric circuits through the mercury of the switch.

15 It is to be understood that I am not limited to the use of the material above mentioned for the different parts of the switch of my invention. For example, the body of the switch 1, the stem coating 5 and 20 the cup 6 are in some cases all made of a soft glass such as lime glass. In other cases they are all made of a boro-silicate glass. In either case the sleeve 7 is made either of lime glass, boro-silicate glass, or fused quartz 25 with a graded seal between the envelope and the cup when they are of different material. Also in some cases I make the cup 6 of boro-silicate glass and the envelope 1 of a soft glass such as lime glass and connect them 30 through a suitable graded seal in the manner well known in the art. The electrodes 2 and 4 are in some cases made of nickel, or iron, or dumet wire.

I claim—

35 1. In a mercury switch having a sealed envelope of glass, electrodes sealed therethrough and terminating therein, one of which has mounted about the end thereof a cup of vitreous material opening into the envelope and having integral connection with said envelope through a sleeve of vitreous material covering said electrode between the cup and the envelope wall, and an integral lining within said envelope and spaced apart 40 therefrom at a short distance and positioned across the shortest path between the envelope wall and any part forming position which said conductors can assume in any 45 position of the switch.

50 2. In a mercury switch having a sealed envelope of glass, electrodes sealed therethrough and terminating therein, one of which has mounted about the end thereof a cup of vitreous material opening into the envelope and having integral connection with said envelope through a sleeve of vitreous material covering said electrode between the cup and the envelope wall, and an integral lining within said envelope and spaced apart 55 therefrom at a short distance and positioned across the shortest path between the envelope wall and any part forming position which said conductors can assume in any 60 position of the switch.

65 3. In a mercury switch having a sealed

envelope of glass, electrodes sealed therethrough and terminating therein, one of which has mounted about the end thereof a cup of vitreous material opening into the envelope and having integral connection 70 with said envelope through a sleeve of vitreous material covering said electrode between the cup and the envelope wall, and an integral lining within said envelope and spaced apart therefrom at a short distance and 75 extending substantially throughout the length of the envelope.

4. In a mercury switch having a sealed envelope of glass, electrodes sealed therethrough and terminating therein, one of which has mounted about the end thereof a cup of vitreous material opening into the envelope and having integral connection 80 with said envelope through a sleeve of vitreous material covering said electrode between 85 the cup and the envelope wall, and an integral lining of fused silica within said envelope and spaced apart therefrom at a short distance and extending substantially 90 throughout the length of the envelope.

5. In a mercury switch having a sealed envelope of glass, electrodes sealed therethrough and terminating therein, one of which has mounted about the end thereof a cup of vitreous material opening into the envelope and having integral connection 95 with said envelope through a sleeve of vitreous material covering said electrode throughout between said cup and envelope, and an integral lining within said envelope 100 and spaced apart therefrom at a short distance and extending substantially throughout the length of the envelope.

6. In a mercury switch having a sealed envelope of glass, electrodes sealed therethrough extending downwardly thereinto and terminating therein, one of which has mounted about the end thereof a cup of vitreous material opening into the envelope and having integral connection with said 110 envelope through a sleeve of vitreous material covering said electrode between the cup and the envelope wall, and an integral lining within said envelope and spaced apart 115 therefrom at a short distance and extending substantially throughout the length of the envelope.

7. In a mercury switch having a sealed envelope of boro-silicate glass, electrodes sealed therethrough and terminating therein, one of which is of tungsten and has mounted about the end thereof a cup formed of fused silica opening into the envelope and having integral connection with said envelope through a sleeve of vitreous material covering said electrode throughout between said cup and said envelope and embodying a graded seal of fused silicates and borates between said boro-silicate envelope 125 and said fused quartz cup.

8. In a mercury switch having a sealed envelope of boro-silicate glass, electrodes sealed therethrough and terminating therein, one of which is of tungsten and has mounted about the end thereof a cup formed of fused silica opening into the envelope and having integral connection with said envelope through a sleeve of vitreous material covering said electrode throughout between said cup and said envelope and embodying a graded seal of fused silicates and borates between said boro-silicate envelope and said fused quartz cup.
9. In a mercury switch having a sealed envelope of vitreous material, electrodes sealed therethrough extending thereinto and terminating therein, one of which has mounted about the end thereof a cup of vitreous material opening into the envelope and having integral connection with said envelope through a sleeve of vitreous material covering said electrode between the cup and the envelope wall, said cup having a protecting ring interposed thereon about the edge of the opening thereof of a more highly refractory material.
10. In a mercury switch having a sealed envelope of vitreous material, electrodes sealed therethrough extending thereinto and terminating therein, one of which has mounted about the end thereof a cup of vitreous material opening into the envelope and having integral connection with said envelope through a sleeve of vitreous material covering said electrode between the cup and the envelope wall, said cup having a rim formed integral therewith about the edge of the opening thereof, and a protecting ring of fused silica interposed on said
- rim and cemented thereon with fused silver chloride.
11. In a mercury switch having a sealed envelope of vitreous material, electrodes sealed therethrough extending thereinto and terminating therein, one of which has mounted about the end thereof a cup of vitreous material opening into the envelope and having integral connection with said envelope through a sleeve of vitreous material covering said electrode between the cup and the envelope wall, said cup having a rim formed integral therewith about the edge of the opening thereof, and a protecting ring of fused silica interposed on said rim and cemented thereon with fused silver chloride and an integral lining of fused silica within said envelope and spaced apart therefrom at a short distance.
12. In a mercury switch, a sealed envelope of vitreous material, electrodes sealed into said envelope a lining in said envelope between the wall thereof and the terminals of said electrodes, a sleeve of vitreous material formed about each of said electrodes having integral connection with the wall of said envelope and extending to and terminating at a position within said sleeve and leaving a portion of the electrode thereat exposed for electrical contact, one of said sleeves having formed integral therewith a cup of vitreous material about the electrode terminal and opening into the envelope, and a body of mercury in the envelope.

Signed at Hoboken, in the county of Hudson and State of New Jersey, this 20 day of April A. D. 1925.

WARREN R. WALKER.
